CLAIM

The ornamental design for a solar backpack as shown and described.

DESCRIPTION

FIG. 1 is a front perspective view of the solar backpack showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is an exploded perspective view showing certain internal details of an embodiment of the solar backpack; and, FIG. 9 is a back view of a solar panel that is inserted into the solar backpack.

If present, dotted lines shown in the accompanying drawings illustrate environmental features in the figures in which they appear. The broken lines showing portions of the solar backpack are for the purpose of depicting environmental structure and form no part of the claimed design.
